UNITED STATES PATENT OFFICE.

90 ROGER W. POLK, OF ST. LOUIS, MISSOURI, ASSIGNOR TO LACLEDE-CHRISTY CLAY
PRODUCTS COMPANY, OF ST. LOUIS, MISSOURI, A CORPORATION OF MISSOURI.

GAS-GENERATOR.

95 1,264,207.

Specification of Letters Patent. Patented Apr. 30, 1918.

Application filed January 7, 1914. Serial No. 810,823.

To all whom it may concern:

Be it known that I, ROGER W. POLK, a citizen of the United States, residing at St. Louis, in the State of Missouri, have invented certain new and useful Improvements in Gas-Generators, of which the following is a specification.

This invention relates to improvements in gas generators. The object of this invention is to provide a new and improved form of gas generator in which is used a single stand-pipe communicating with a plurality of individual retorts. My invention also contemplates the use of a stand-pipe constructed in sections, said sections being associated to prevent the leakage of gas passing therethrough, at the same time permitting differential or relative expansion to compensate for the expansion of the retorts and their supporting structure.

It is well known that in this type of furnace, where a plurality of retorts are arranged, supported by walls of fire-brick or the like, that retorts at varying levels are raised or lowered, more or less, corresponding to their height from the bottom of the furnace, owing to the expansion of the fire-brick and the like, and it is one object of my invention to permit such expansion to take place without strain being transmitted to the stand-pipes or connecting structure.

These and other objects will be set forth and fully described in the accompanying specification, and shown in the accompanying drawings, in which:

Figure 1 is a front elevation of one embodiment of my invention;

Fig. 2 is a vertical section of the form shown in Fig. 1;

Fig. 2^a is a vertical section through the portion of the stand-pipe and the sewer or collection duct.

Like numerals refer to like elements throughout the drawings, in which:

10 designates the front wall of a furnace, through which project the front ends or mouthpieces 11 of a plurality of retorts 12.

Each of these retort mouthpieces projects 50 outwardly of the front wall, as indicated in Fig. 3 for example, and is provided with the elbow 13, adapted to be secured to and communicate with an elbow 14 carried by stand-pipe section 15. The elbows 13 and 55 14 are inclined downwardly from the re-

tort 12 and furnish a means of communication from the interior thereof to the corresponding stand-pipe section 15. The stand-pipe generally indicated by numeral 16, comprises a plurality of these sections 60 15, which, in the form shown, communicate with a retort on each side thereof, as in the structure described above, and as clearly shown in Fig. 1. Leakage between adjacent extremities of these sections is prevented by 65 a fluid seal construction, clearly shown in Fig. 2, where the seal is generally indicated by the numeral 17. A cup member 17^a, terminating in the downwardly projecting sleeve 17^b, which fits over and is secured to 70 one end of the stand-pipe section, is provided with the upwardly extending flanges 17^c, 17^d, approximately parallel and spaced apart, thereby forming a peripheral or annular container, indicated by numeral 17^e, 75 in which is adapted to be contained a fluid, such as water or the like. The adjacent stand-pipe section is provided with the offset, downwardly extending peripheral flange 18, adapted to project downwardly into 80 the annular chamber 17^e and be spaced from the flanges 17^c, 17^d. Flange 17^d extends upwardly some distance above the flange 18, and a cap or cover 19, which may be formed of two sections, elevated or otherwise secured together, as indicated at 19^a, rests 85 upon the upper end of such flange and closely fits around the adjacent pipe section.

It will be apparent that when the chamber 17^e is filled with water or other fluid, 90 gas at ordinary working pressure will be prevented from leaking from between the ends of the adjacent pipe sections, and this construction will at the same time permit relative expansion of the adjacent sections. 95 To provide means for supplying fluid, as needed, to the chamber 17^e an outwardly extending pipe or tube 20 is provided with the upwardly extending portion 20^a which carries a funnel 20^b. A supply pipe 21 may 100 be provided emptying into the funnel 20^b, flow of fluid therethrough being controlled by a suitable valve or the like.

While I have only described one of the seals in detail, all of the seals shown for 105 example are of similar construction and need no further detail description.

Upwardly of the seal 25 is provided a gate or similar valve indicated by numeral 26 and upwardly thereof the stand-pipe 16 110

communicates with the offtake generally indicated by numeral 27. Upwardly of the offtake, and in alinement with the stand-pipe 16, is provided a cap or plug 28 removal of which will permit cleaning of the stand-pipe 16 from the exterior thereof.

In this form, the flow of gas is from the retorts upwardly through the stand-pipe 16 to the offtake 27. To provide means for preventing deposit of carbon or other non-volatile substances on the interior wall of the stand-pipe 16, a spray 30 is located adjacent the upper end of the stand-pipe 16. Fluid is supplied thereto by the pipes 31, 32, and the action of the spray 30 is such as to spray the gas with finely divided or atomized water or other fluid on the interior wall of the stand-pipe 16, at the upper portion thereof, so that the same will run down the sides thereof and maintain the same at a reduced temperature; also any carbon or other substances tending to deposit on this inner wall will be gathered by the down-running water or other fluid and carried downwardly through the stand-pipe 16 to the trough 35, the lower end 16^a of the stand-pipe projecting below the level of the water or other fluid in the trough 35. Openings 35^a, 35^b may be provided in the ends of the trough 35 to provide an overflow therefor and to permit draining thereof, as needed. The lower end 16^a of the stand-pipe 16, is offset and connected with the main portion thereof by the inclined portion 16^b. An elbow portion 16^c extends upwardly from the junction of the portions 16^a, 16^b and is provided with a removable plug 16^d in its upper end which may be removed for cleaning of the portion 16^c. A door 16^e is provided in the inclined portion 16^b of the pipe, below the main vertical portion of stand-pipe 16.

To supply fluid to each of the seals 17, I provide a supply pipe 36 extending downwardly from the pipe 20 and a plurality of

tubes 37 are provided leading each to one of the seals 17 from the tube 36. A plurality of valves 37^a may be provided to control supply of fluid through the tubes 37. It will be apparent that as the fluid from the spray 30 flows downwardly through the stand-pipe 16, it will be prevented from flowing into the retorts 11 by means of the downward inclination of the ducts comprising sections 13 and 14. At the same time a sheet of water or other fluid will ordinarily flow across the ends of the ducts 14 and tend to purify the gas flowing therethrough.

In some cases a plurality of water-seals 60 may not be necessary and I may construct the stand-pipe with but the single seal 25, thereby providing for general expansion of the furnace and stand-pipe.

It will be apparent that while I have shown and described my improved structure with more or less particularity, the same is susceptible of modification and I do not wish to be restricted to said showing or description beyond the scope of the appended claim.

What I claim is:—

In combination with a plurality of retorts located in different vertical planes, a common stand-pipe in connection with said retorts, supporting structure for said retorts, said stand pipe being formed in relatively movable sections between each of said retorts to permit relative and differential movement of said retorts and fluid sealing means between each of said stand-pipe sections to prevent leaking at the juncture of such sections.

In testimony whereof, I have subscribed my name.

ROGER W. POLK.
